CLAIM

USPC D24/146-147, 200, 216, 231-232,

The ornamental design for an electronic muscle and nervous system stimulator device as shown and described.

D24/165-168, 110, 214, 209, 206,

DESCRIPTION

D24/186-187, 140, 133, 135; D3/210;

The patent or application file contains at least one drawing executed in color. Copies of this patent or patent application publication with color drawing(s) will be provided by the Office upon request and payment of the necessary fee.

D8/354, 80, 47; D15/5, 9, 9.2, 9.1, 7;

Figure 1.1 is a front, left, top perspective of an electronic muscle and nervous system stimulator device, showing my new design;

D10/2; D14/216

Figure 1.2 is a front elevation view thereof;

CPC A61G 2203/36; A61B 2503/02; A61B

Figure 1.3 is a left side elevation view thereof;

5/0444; A61B 5/0448; A61B 5/0432;

Figure 1.4 is front, left, bottom perspective view thereof;

A61B 5/02411; A61B 5/0011; A61B

Figure 1.5 is a left, front view thereof; and

5/4343; A61B 5/4362; A61B 5/4356;

Figure 1.6 is another front, left, top perspective view thereof.

A61B 5/6833; A61B 5/0478; A61B

(Continued)

5/0205; A61B 5/02055; A61B 5/02405;

A61B 5/02444; A61B 5/4809; A61B

5/1102; A61B 5/6801; A61B 5/6802;

A61B 5/6813; A61B 5/6814; A61B

5/6815; A61B 5/6816; A61B 5/6817;

A61B 5/6818; A61B 5/6819; A61B

5/6822; A61B 5/6823; A61B 5/6824;

The PULSETO forming part of the claimed design is a registered trademark of UAB Pulsetto.
